UNITED STATES PATENT OFFICE.

GEORGE M. CLARKE, OF ROCHESTER, NEW YORK, ASSIGNOR TO WEAVER,
PALMER & RICHMOND, OF SAME PLACE.

DEVICE FOR HOOPING WOODEN VESSELS.

SPECIFICATION forming part of Letters Patent No. 624,178, dated May 2, 1899.

Application filed November 12, 1898. Serial No. 696,230. (No model.)

To all whom it may concern:

Be it known that I, GEORGE M. CLARKE, a citizen of the United States, residing at Rochester, in the county of Monroe and State of New York, have invented a new and useful Improvement in Devices for Hooping Wooden Vessels, which improvement is fully set forth in the following specification and shown in the accompanying drawings.

10 My invention relates to means for hooping wooden vessels or similar vessels made up of staves or parts joined; and it consists of a strip or band of metal bent to form a hoop for such vessel, with a part for connecting the 15 adjacent ends of the hoop. In this device the strip of metal forming the hoop is not pierced or punctured or formed with indentations or notches of any kind, it being simply bent or doubled back upon itself at its ends.

20 The invention is hereinafter fully described, and more particularly pointed out in the claims.

Referring to the drawings, Figures 1 and 2 show, respectively, the outside and inside 25 faces of the connecting-piece for the ends of the band or hoop. Fig. 3 shows the adjacent ends of the hoop bent in place in the connecting piece or holder, a part of the latter being broken away. Fig. 4 shows the inner face of 30 the holder and the bent ends of the hoop. Fig. 5 shows an edge view of the ends of the hoop and the holder, the adjacent part of the vessel being horizontally sectioned at the edge of the holder. Fig. 6 is an end view of the 35 holder for the hoop, the latter being cross-sectioned as on the dotted line 6 6 in Fig. 3. Fig. 7 is an end view of the holder, the hoop being omitted. Fig. 8 is a longitudinal section of parts, taken on the dotted line 8 8 in 40 Fig. 9. Fig. 9, drawn to a smaller scale, shows the adaptation of the device to the vessel.

Referring to the drawings, A is a wooden vessel, such as a tub or pail, or it may be a barrel or other similar device slightly tapered 45 or flaring for the purpose of receiving metallic binding-hoops.

B is a simple strip of hoop metal, C being a connecting-piece or holder for the ends of said metal strip when the latter is bent to a 50 circular form. The piece C is a thin rectan-

gular metal plate or body, which, together with the part B, constitutes a hoop proper for the vessel. The connecting-piece C, preferably made of firm sheet metal or malleable iron, is longer than it is wide and wider than the strip B and is formed with a central transverse opening h, through which the ends of the metal strip are passed when the hoop is being formed. This opening is slightly longer than the width of the metal strip B and wider than twice the thickness of said strip, so that both ends of the latter may pass through the opening and occupy it together.

In forming the opening h the metal of the plate is pressed upward or outward, which part thus pressed out forms a raised bridge a. This part or bridge a is cut clear of the original plate C at the sides, but left attached or uncut at the ends, the plate when thus formed being a single piece and without detached parts. The bridge a is raised sufficiently high to leave openings b b at its sides to receive through them the respective ends of the strip B, as shown in Figs. 3 and 8. The bridge covers the opening h and also the adjacent parts of the strip B when bent around the opposing edges of the wings c c of the plate C. This connecting-piece C is curved transversely to correspond to the curvature of the vessel A, to which it is to be applied.

The metal strip B when in place on the connecting-piece C rests against the outer surface of said piece or upon the upper surfaces of the two parts or wings c c at either side of the opening h, with its ends i bent or turned backward beneath said wings, as appears in Fig. 8. The edges d d of the wings are bent downward or depressed longitudinally, as appears in Figs. 6 and 7, forming longitudinal chambers or depressions e e in the inner face of the plate in which to receive the inwardly-turned ends i of the metal strip. The inner faces g g g g of the depressed edges are in line or even with the respective inner surfaces of the inturned ends of the metal strip. The bends at the edges d are offset bends—that is to say, the surfaces g are parallel with the original surface of the plate C or the upper surfaces f f of the wings. The depths of the chambers e e being equal to the thickness of

the metal strip, the latter is completely covered or hidden from view where occupying said chambers, the surfaces *g* meeting and resting against the outer surface of the staves 5 of the vessel, as appears in Fig. 5.

In applying this device to the vessel to be hooped one end of the strip *B*, first cut to the required length, is passed through an opening *b* at one side of the bridge and inward 10 through the opening *h* and bent or doubled back upon itself, as shown in Fig. 8. In making this bend the strip is carried around the inner edge of a wing *c* of the plate *C* under the bridge, said wing engaging and holding 15 the strip against a longitudinal pull or stress. The strip is then carried or bent around the vessel at the place it is to occupy and marked at the other side of the bridge, after which the marked end is passed through the other 20 opening *b* and the opening *h* and doubled or bent backward at the mark made, as in the first instance. It is then ready to drive upon the tapered vessel in the ordinary manner. When thus put upon the vessel, the inner 25 surfaces of the inturned ends *i* of the strip bear directly against the side of the vessel, the extreme ends of the strip being under the

parts of the latter passing over the outside of the plate *C*.

What I claim as my invention is—

1. A connector struck from a single piece 30 of metal and comprising an apertured plate, a raised bridge covering the aperture, and depressed longitudinal edges, said connector having a slight longitudinal curvature, substantially as specified.

2. The combination with a hoop, of a connector comprising a plate having a transverse aperture and a bridge above the aperture, the longitudinal edges of the plate being depressed along their entire lengths, the ends of the hoop being passed through the aperture and bent under the plate in opposite directions between the depressed edges, the under faces of the hoop ends and depressed 40 edges lying in the same plane, substantially 45 as specified.

In witness whereof I have hereunto set my hand, this 8th day of November, 1898, in the presence of two subscribing witnesses.

GEORGE M. CLARKE.
